UNITED STATES PATENT OFFICE.

LUCIEN A. BUTTS, OF RUSSELL, IOWA.

FENCE-WIRE STRETCHER.

SPECIFICATION forming part of Letters Patent No. 751,608, dated February 9, 1904.

Application filed April 1, 1903. Serial No. 150,633. (No model.)

To all whom it may concern:

Be it known that I, LUCIEN A. BUTTS, a citizen of the United States, residing at Russell, in the county of Lucas and State of Iowa, have 5 invented a new and useful Wire-Stretcher, of which the following is a specification.

This invention relates to certain improvements in wire-stretchers of that general class shown in United States Letters Patent granted 10 to me on the 17th day of May, 1887, under No. 363,314.

The primary object of the invention is to improve, simplify, and cheapen the construction of the stretcher and to provide means for effectually stretching and retaining the wire under tension preparatory to nailing, stapling, or otherwise permanently securing the wire to the fence-post.

A further object of the invention is to provide 20 novel means for clamping the stretcher to the fence-post, thereby effectively preventing vertical or lateral displacement of the same during the stretching operation, and, furthermore, to provide a stretcher, the construction 25 and relative disposition of the several parts being such as to permit them to be readily assembled or any part thereof removed and renewed when worn or broken.

The invention consists in the construction 30 and novel combination and arrangement of parts hereinafter fully described; illustrated in the accompanying drawings, and pointed out in the claims hereto appended, it being understood that various changes in form, proportion, and minor details of construction may 35 be resorted to without departing from the principle or sacrificing any of the advantages of this invention.

In the accompanying drawings, Figure 1 is 40 a perspective view of a wire-stretcher constructed in accordance with my invention, showing the same applied to a fence-post. Fig. 2 is a top plan view of the same. Fig. 3 is a side elevation. Fig. 4 is a front elevation of the stretcher. Fig. 5 is a rear view of the sectional base and supporting-arms. Fig. 45 6 is a side elevation of the base and supporting arms with the shaft or spindle removed.

Fig. 7 is a front elevation of a modified form of stretcher, showing a pair of vertically-disposed pins for attaching the wire to the shaft or spindle. Fig. 8 is a side elevation of the wrench or spanner.

Similar numerals of reference indicate corresponding parts in all the figures of the drawings.

1 designates the supporting-base, which may be formed of metal or other suitable material, and consists of a pair of horizontally-disposed bars 2 and 3, provided, respectively, with upwardly and downwardly extending lugs or ears 4, adapted to bear against the side of the fence-post. The ends of said lugs are forked, as shown at 5, for the reception of screws or similar fastening devices, which may engage the 60 post and prevent vertical displacement of the stretchers when necessary. The bars 2 and 3 are each provided with a series of coincident openings 6, and pivoted in said openings at the opposite ends of the bars are horizontally-projecting arms 7 and 8, the inner faces of which are provided with inwardly-extending teeth 9, which engage the sides of the post. The arms 7 and 8 are clamped to the post by means of a threaded bolt 10, the hooked end 75 11 of which engages an opening in the end of the arm 7, the opposite end of the bolt passing through upwardly-extending ears 12 on the end of the arm 8 and engaging a wing-nut 13. Formed integral with the base is a 80 pair of supporting-arms 14 and 15, the rear ends of which are reduced, as shown at 16, forming a spacing-block for the bars 2 and 3, said supporting-arms being secured together by means of a bolt and nut 17, passing through 85 alined openings in said bars. The forward ends of the arms 14 and 15 are provided with semicircular sockets, as shown, which when secured together form a sleeve 18, adapted to embrace a sectional hollow shaft 19, provided 90 with ratchet-toothed collars or rings 20 and 21, which abut one on either side of the sleeve 18. The collar 20 is keyed to the shaft by means of outwardly-extending pins or lugs 22, formed on the periphery of each section comprising the 95 shaft, which engage corresponding openings

formed in said collar, the collar 21 being secured to the shaft by a pin 23, passing transversely through the shaft and fitting in recesses formed in the side of the collar 21. A pawl 24 is pivoted to the supporting-arms 14 and 15 by means of a bolt and nut 25, which passes through an opening 26, formed in the adjacent faces of said arms, and this pawl is adapted to engage the toothed collar 21 when the shaft is rotated and prevent the wire from slipping, as will be more fully explained hereinafter. The opposite ends of the shaft 19 are provided with longitudinally-disposed slots or openings 27, adapted to receive the ends of the wire and firmly grip the same when the device is in operation, the surplus wire being wound on the ends of the shaft.

28 indicates a spanner or wrench provided with an inwardly-extending tooth 30, which 20 engages the teeth on the collar 22 and by means of which the shaft is rotated.

The construction of the device will be readily understood and the operation thereof is as follows: In practice the stretcher is placed in 25 position with the supporting-base resting flat against the post and the horizontal arms 7 and 8 embracing the sides thereof, the stretcher being securely clamped to the post by tightening the nut 13 and prevented from tilting 30 or tipping when stretching the wire by means of the forked ears or lugs, as clearly shown in Fig. 1 of the drawings. The wire is now passed through the longitudinal slot in the end of the shaft and said shaft rotated by applying 35 the wrench or spanner to the toothed collar 20 and turning the same, the wire being bent and firmly gripped in the slot and the surplus or slack wound on the end of the shaft as the wire is stretched. As the shaft is turned 40 the pawl 24 engages the tooth-collar 21, securely holding the wire under the desired tension while nailing, stapling, or otherwise permanently securing the same to the fence-post.

In some cases the clamping-arms 8 and 9 45 may be dispensed with, the stretcher being held in position on the post by means of screws or similar fastening devices passing through the slots in the ears or lugs 4 and engaging the post.

50 In Fig. 7 I have shown the shaft or spindle 19 provided with transversely-disposed pins 31 for holding the wire while turning the shaft instead of the slots or openings 27.

From the foregoing description it will be 55 seen that I have provided a stretcher that is extremely simple in construction and effective in operation, which may be easily and quickly applied to a post or other structure, and being composed of several parts detachably secured together should any one of the parts become worn or broken it may be quickly removed and renewed.

Having thus described the invention, what

I claim, and desire to secure by Letters Patent, is—

1. A wire-stretcher, comprising, a base, a pair of supporting-arms secured to the base and provided with semicircular bearing-plates extending the entire width of the arms, a revolving shaft mounted in the bearing-plates, 70 means carried by the shaft for engaging a wire, means for adjustably supporting the stretcher, and means for locking the shaft to hold the stretched wire.

2. A wire-stretcher, comprising, a base provided with outwardly-projecting ears, a pair of horizontally-disposed supporting-arms secured to the base and provided with semicircular bearing-plates extending the entire width of the arms, a revoluble shaft mounted 80 in the bearing-plates and having wire engaging means, a toothed collar secured to the shaft, a pawl pivoted to the supporting-arms and adapted to engage the toothed collar, means for adjustably supporting the stretcher 85 and means for rotating the shaft.

3. A wire-stretcher, comprising, a sectional base, sectional supporting-arms secured to the base and provided with semicircular bearing-plates, a revoluble shaft mounted in the bearing-plates, a pair of toothed collars secured to the shaft and adapted to abut one on each side of said bearing-plates, a pawl carried by the supporting-arms and adapted to engage one 90 of the toothed collars, means carried by the shaft for engaging a wire, and means for securing the stretcher to a fence-post.

4. In a wire-stretcher, the combination, of a base consisting of a pair of horizontally-disposed spaced bars provided with outwardly-extending ears, sectional supporting-arms formed integral with the base and provided with semicircular bearing-plates, a shaft revolubly mounted in said bearing-plates, said shaft having slotted end portions, a pair of 100 toothed collars secured to the shaft and abutting one on each side of the bearing-plates, a pawl pivoted to the supporting-arms and adapted to engage one of the toothed collars, means for clamping the stretcher to a post 110 and an actuating means for engaging the second collar.

5. A wire-stretcher comprising a sectional base, sectional supporting-arms secured to the base, a shaft revolubly mounted in the supporting-arms, said shaft having slotted end portions, a pair of toothed collars on said shaft, a pivoted pawl carried by the supporting-arms and adapted to engage one of said toothed collars, a pair of toothed arms pivoted to the 115 sectional base, and means for clamping the arms to a post.

6. A wire-stretcher comprising a sectional base, sectional supporting-arms secured to the base, a shaft revolubly mounted in the supporting-arms, said shaft having slotted end portions,

tions and provided with a pair of fixed toothed collars, a pivoted pawl adapted to engage one of said collars, a pair of adjustable toothed arms pivoted to the base, a clamping-screw passing through the ends of said toothed arms, a nut adapted to engage the screw, and means for rotating the shaft or spindle.

In testimony that I claim the foregoing as my own I have hereto affixed my signature in the presence of two witnesses.

LUCIEN A. BUTTS.
